Primary Examiner — Elizabeth J Oswecki(74) *Attorney, Agent, or Firm* — Craig R. Miles; CR Miles P.C.(57) **CLAIM**

The ornamental design for a water shoe, as shown and described.

DESCRIPTION

FIG. 1 is a top left side perspective view of a water shoe showing our new design;

FIG. 2 is a right side elevation view thereof;

FIG. 3 is a left side elevation view thereof;

FIG. 4 is a front elevation view thereof;

FIG. 5 is a back side elevation view thereof;

FIG. 6 is a top plan view thereof; and,

FIG. 7 is a bottom plan view thereof.

The broken lines shown are included for the purpose of illustrating the unclaimed portions of the article and form no part of the claim.
